DESIGN FOR A PEN OR LIKE ARTICLE

Eugene Douglas, Brooklyn, N. Y.

Application February 28, 1947, Serial No. 137,218

Term of patent 14 years

(Cl. D74—17)

To all whom it may concern:

Be it known that I, Eugene Douglas, a citizen of the United States, residing at Brooklyn, in the county of Kings, in the State of New York, have invented a new, original, and ornamental Design for a Pen or Like Article, of which the following is a specification, reference being had to the accompanying drawing, forming a part thereof.

Fig. 1 is a plan view of a pen or like article, showing my design; Fig. 2 is a front elevational view of the same; Fig. 3 is a side elevational view of the same; Fig. 4 is a bottom plan view of the same.

I claim:

The ornamental design for a pen or like article, as shown.

EUGENE DOUGLAS.
